UNITED STATES PATENT OFFICE

161,644

EMBROIDERY KIT

Celia Rabinowitz, Brooklyn, N. Y.

Application July 26, 1950, Serial No. 11,418

Term of patent 3½ years

(Cl. D3—19)

To all whom it may concern:

Be it known that I, Celia Rabinowitz, a citizen of the United States, residing at 910 DeKalb Avenue, Brooklyn, in the county of Kings and State of New York, have invented a new, original, and ornamental Design for an Embroidery Kit, of which the following is a specification, reference being had to the accompanying drawing, constituting a part hereof:

Fig. 1 is a perspective view of an embroidery kit, showing my new design.

Fig. 2 is a top plan view,

Fig. 3 is a side elevational view,

Fig. 4 is a side elevational view of the opposite side, and

Fig. 5 is an end elevational view.

I claim:

The ornamental design for an embroidery kit, substantially as shown.

CELIA RABINOWITZ.
